CLAIM

The ornamental design for a panel with pattern, as shown and described.

DESCRIPTION

This application is a continuation application of U.S. application Ser. No. 14/998,010, filed Mar. 8, 2015, and entitled Panels and Tiles Having Various Patterns, the entire content of which is incorporated herein by reference in its entirety. FIG. 1 is a front perspective view of a panel with pattern as used in a partition;

FIG. 2 is a front perspective view thereof;

FIG. 3 is a front elevational view thereof;

FIG. 4 is a cross-sectional view taken in the direction of line 4-4 in FIG. 3;

FIG. 5 is a cross-sectional view taken in the direction of line 5-5 in FIG. 3;

FIG. 6 is a cross-sectional view taken in the direction of line 6-6 in FIG. 3; and,

FIG. 7 is a cross-sectional view taken in the direction of line 7-7 in FIG. 3.

The broken lines in the drawings depict environment that forms no part of the claimed design.
